UNITED STATES PATENT OFFICE.

THEODORE H. BOLTE, OF KEARNEY, NEBRASKA, ASSIGNOR OF ONE-HALF TO EDWARD F. BOLTE, OF EAU CLAIRE, WISCONSIN.

CONCRETE-MIXER.

No. 898,958.

Specification of Letters Patent. Patented Sept. 15, 1908.

Application filed March 7, 1908. Serial No. 419,568.

To all whom it may concern:

Be it known that I, THEODORE H. BOLTE, a citizen of the United States, residing at Kearney, in the county of Buffalo and State 5 of Nebraska, have invented certain new and useful Improvements in Concrete-Mixers; and I do hereby declare the following to be a full, clear, and exact description of the invention, such as will enable others skilled in the 10 art to which it appertains to make and use the same.

My invention has for its object to provide an improved concrete mixer; and to this end, the invention consists of the novel devices 15 and combinations of devices hereinafter described and defined in the claims.

The invention is illustrated in the accompanying drawings wherein like characters indicate like parts throughout the several 20 views.

In said drawings; Figure 1 is a side elevation of the machine, with some parts broken away. Fig. 2 is a plan view of the same. Fig. 3 is a vertical longitudinal section 25 through the machine, with some parts broken away and others shown in elevation, looking in the same direction as in Fig. 1; and Fig. 4 is a cross section through a part of the machine, on the line $x^4 x^4$ of Fig. 3.

The numeral 1 represents a skeleton frame 30 of suitable form to support the working parts of the machine, and to be mounted, when desired, on supporting trucks 2. As shown, the axle of the rear truck is rigid with the 35 frame, and the axle of the forward truck is pivoted thereto through a bolster 3 fixed to the frame and pivoted to the truck axle.

The numerals 4, 5 and 6 represent, respectively, the shaft, the spiders and the 40 shell of an open-ended mixing cylinder which is mounted for rotary motion on the main frame, with the cylinder and shaft extending lengthwise thereof and at an angle or downward incline from the front toward the rear 45 of the machine. The cylinder shaft 4 is mounted, at its rear end, in a bearing 7 supported by hanger 8 depending from the top bars of the main frame 1; and the said shaft 4 is supported, at its upper or forward end, 50 in a bearing 9 fixed to one of the cross bars of the said main frame 1. On the interior of the shell 6 of the mixing cylinder are preferably located spiral or conveying flights 10 extending lengthwise of the cylinder, and 55 throughout the central zone of the same,

thus leaving the cylinder free from flights at its receiving and delivery ends. At its upper end, the shaft 4 is provided with a bevel gear 11 which is engaged by a bevel pinion 12 on driving shaft 13 which is mounted in suitable bearings fixed to the front standards of the main frame 1. The driving shaft 13 is provided, at one end, with a driving crank-equipped pulley 14 for imparting power either by hand or by belt. 60

The numeral 15 represents a suitable endless feed belt shown as mounted on rollers 16 supported by a frame 17, with the said parts properly disposed to cause the belt to extend and travel in a general direction lengthwise 70 of the shaft of the mixing cylinder and directly below the same. Diagonal braces or brackets 18 support the lower end of the roller frame 17 from the main frame 1 of the machine. The forward member of the rollers 16 is provided with a shaft 19 which extends outward and is mounted in suitable bearing boxes fixed to the forward standards of the main frame. One end of the shaft 19 extends outward beyond the main frame and 80 is provided with a sprocket wheel 20 which is connected by chain 21 with a relatively small sprocket wheel 22 on the driving shaft 13. The roller frame 17 rests, at its forward end, on the shaft 19, as shown, but might, 85 of course, be supported directly from the main frame 1. With said sprocket and chain connections 20, 21 and 22, it is obvious that the forward member of the rollers 16 supporting the feed belt 15 will receive rotary motion 90 from the driving shaft 13, and that, thereby, the endless feed belt 15 will be kept in continuous motion with its upper running fold or top surface moving toward the mixing cylinder. 95

Directly above the feed belt 15, and in tandem arrangement in respect to each other and in respect to the mixing cylinder, are located a pair of supply hoppers 23 and 24, respectively, the hopper 23 being for cement 100 and the hopper 24 for the sand or mixture of sand and gravel or fine broken stone. The upper or receiving ends of the hoppers 23 and 24 extend entirely across the main frame, thereby enabling the sand or the cement to 105 be supplied thereto from either side of the machine.

The lower or small ends of both hoppers 23 and 24 are closed only by the directly underlying feed belt 15, the belt being so mounted 110

that it runs close to the lower edges of the walls of the said hoppers. The rear wall of the sand hopper 24 is provided with a discharge opening or slot controlled by sliding gate 25 mounted in the said wall under sufficient friction to remain in any position where set. The cement hopper 23 is provided with a similar slot in its rear wall controlled by sliding gate 26, also so supported that it will 10 stay in whatever position it may be set. As shown, the discharge outlets of the two hoppers are staggered in respect to each other crosswise of the belt, so that the sand will be delivered to one longitudinal zone of the belt and the cement to another longitudinal 15 zone of the belt, thereby insuring a free feed of the sand and cement from the respective hoppers. An apron or guard board 27 is fixed to the main frame directly in front of 20 the cement hopper 23, thereby affording a convenient rest for the bags of cement when emptying the same into the hopper from the front of the machine.

The cement is fine and heavy and does not 25 require any forced feed to get it out of the hopper 23 when in its dry or in proper mixing condition. It is desirable, however, to have some feeding device for the sand which will prevent the same from clogging at the lower 30 end or discharge outlet from the hopper 24. For this purpose, and for the further purpose of lowering this hopper very materially, I extend the shaft 4 of the mixing cylinder through the lower end of the sand hopper 24, 35 and provide the same with a series of radial feeding pins or spikes 28, as best shown in Fig. 3. These pins will keep the sand loosened up and insure its free discharge through the outlet controlled by the gate 25.

40 The numeral 29 represents a water tank supported from the top side bars of the main frame, and provided with a delivery pipe 30 bent upon itself and extending into the lower or delivery end of the mixing cylinder. Said 45 pipe 30 is provided with a hand valve 31 and the delivery end of the pipe is perforated to secure a jet or shower discharge of the water onto the commingled sand and cement.

The operation of the machine is probably 50 obvious from the above given specification of the parts. The hoppers 23 and 24 and their discharge outlets are so proportioned that when the respective gates 25 and 26 controlling said outlets have been properly set, 55 the cement and the sand will be fed therefrom in proper proportions onto the endless feed belt, when the machine is in motion, and be delivered thereby into the upper or receiving end of the mixing cylinder. Hence, if it 60 be assumed that the machine is in motion and that the hoppers 23 and 24 are kept supplied with sand and cement, respectively, and that the shower of water is available from the water tank, then the action is as 65 follows: The sand and the cement are deliv-

ered from the hoppers to the feed belt, and by said feed belt to the receiving end of the mixing cylinder in proper proportion to each other and in a dry condition. Then, under the rotation of the cylinder, the sand and the 70 cement will be thoroughly commingled together before reaching the zone of the cylinder which is supplied with a shower of water. In this mixing action, the spiral flights lift up the material until it drops therefrom by 75 gravity to the bottom of the cylinder, and under the conveying action of the flights and the co-operative action of gravity, the material will be forced toward the delivery end of the cylinder and out therefrom. The sprinkling zone is of sufficient length to continue 80 the mixing action after the water begins to fall on the material for a long enough time to thoroughly incorporate the water. Hence, the concrete as delivered from the machine is 85 ready for use.

It must be obvious that this is an efficient and convenient machine which is simple and cheap to make, and which can be utilized with a minimum of labor. The truck wheels 2 are 90 of small diameter, and in virtue of the fact that the mixing cylinder is set low on the main frame, and that the hoppers extend below the shaft of said cylinder with the feed belt directly underlying the same, the upper 95 ends or receiving mouths of the hoppers are brought to a low level in respect to the ground. It, of course, follows that the sand and cement do not have to be lifted so high to be put into the hoppers. This is highly material, especially in respect to the sand, large quantities of which are used, and which is shoveled from the ground into the sand hopper. From the fact that the hoppers 23 and 100 24 extend entirely across the machine, the sand and cement can be supplied from either side of the machine, and the cement hopper 23 is so located that it may be supplied also from the front of the machine.

105 It will be understood, of course, that the various working parts may be made of any suitable material, as long as the same is adapted for the purposes had in view. For example, the feed belt may be of rubber, leather, canvas or flexible sheet steel or other 110 metal.

115 What I claim is:—

1. In a concrete mixer, the combination with a rotary mixing cylinder and a pair of supply hoppers, one for the sand and the other for the cement, set tandem with respect to each other and the cylinder, and provided with gate controlled discharge outlets 120 staggered with respect to each other crosswise of the underlying feed belt, and an endless feed belt extending in the general direction of the axis of said cylinder with its upper running fold forming the bottom walls of 125 said hoppers and operative to receive the sand and cement on different zones thereof 130

and to deliver the same directly into the receiving end of said cylinder, substantially as described.

2. The combination with the rotary mixing cylinder and means for supplying water to the interior of the lower or delivery end portion of said cylinder, of the pair of supply hoppers, one for sand and the other for cement, set tandem with respect to each other and the cylinder and having the staggered gate controlled discharge outlets, the endless feed belt extending in the general direction of the axis of said cylinder and operative to receive the sand and cement on different zones thereof and to deliver the same to the receiving end of said cylinder, and a drive for imparting motion to said cylinder and feed belt, all for coöperation, substantially as described.
- 20 3. In a concrete mixer, the combination with a rotary mixing cylinder set low on the main frame and at an incline lengthwise thereof, with its shaft extended upward be-

yond the upper or receiving end of said cylinder, of a pair of supply hoppers, one for sand 25 and the other for cement, set tandem with respect to each other and said cylinder, with their lower ends extending below said shaft and said shaft passing through the hoppers and having radial feed pins on that portion 30 thereof located within the sand hopper, and an endless feed belt directly underlying the lower ends of said hoppers and extending in the general direction of the axis of said cylinder with its upper running fold receiving the 35 sand and cement from said hoppers and delivering the same directly into the receiving end of said cylinder, substantially as described.

In testimony whereof I affix my signature 40 in presence of two witnesses.

THEODORE H. BOLTE.
